Attorney.

UNITED STATES PATENT OFFICE.

ISIDORE GOLDMAN, OF LEEDS, ENGLAND, ASSIGNOR TO THE DENTAL MANUFACTURING COMPANY, LIMITED, OF LONDON, ENGLAND.

ARTIFICIAL TOOTH.

1,316,787.

Specification of Letters Patent. Patented Sept. 23, 1919.

Application filed March 25, 1919. Serial No. 285,026.

To all whom it may concern:

Be it known that I, ISIDORE GOLDMAN, a Russian subject, of 105^a North street, Leeds, in the county of York, England, have invented new and useful Improvements in and Relating to Artificial Teeth, of which the following is a specification.

My invention relates to improvements in those artificial teeth in which a pin is mounted centrally in the face of a projection or boss on the rear face of the tooth, this boss serving the purpose of locking the tooth to the vulcanite plate when the tooth is set in position and preventing relative movement between the plate and the tooth while strengthening that portion of the tooth which is usually the weakest part. In teeth of this form the boss also serves the purpose of transmitting the force of the bite directly from the plate to the tooth and relieving the biting stress on the pin.

According to the present invention the boss which may be of any desired form is undercut on all sides, and is combined with a single pin mounted in or near the center of the face of the boss.

My invention is illustrated by way of example in the accompanying drawings, in which

Figure 1 shows a side view of a tooth with a boss of approximately square formation.

Fig. 2 shows a plan view of Fig. 1,

Fig. 3 shows a rear face of Fig. 1, and

Fig. 4 shows a side view of a tooth fitted with a headed pin.

Referring now to the drawings:—

The tooth 1 is provided with a boss 2 which is undercut at 3 on all sides. A platinum or other suitable pin 6 is mounted in 40 or about the center of the boss 2. If desired, as shown in Fig. 4, the pin may be provided with a head 7.

What I claim is:—

An artificial tooth comprising a boss on 45 the rear face of the tooth, undercut sides to said boss and a pin mounted in the face of said boss.

In testimony whereof I sign my name to this specification.

ISIDORE GOLDMAN.
